Attorney.

UNITED STATES PATENT OFFICE

JUAN PEDRO RODRIGUEZ, OF LAKE WORTH, FLORIDA, ASSIGNOR OF ONE-HALF TO
GEORGE W. KRICK, OF LAKE WORTH, FLORIDA

PROPELLER

Application filed August 13, 1930. Serial No. 475,111.

The present invention relates to boat propellers, and aims to provide a novel and improved propeller which will operate efficiently and more smoothly than with the usual bladed propeller.

Another object of the invention is the provision of a propeller which will also serve as a flywheel, and which is rugged in construction so as not to be apt to break in striking 10 obstructions.

The invention is illustrated in the accompanying drawing, wherein—

Figure 1 is a side elevation of a push propeller constructed in accordance with the 15 present invention.

Fig. 2 is a rear end view thereof.

Fig. 3 is a cross section on the line 3—3 of Fig. 1.

Fig. 4 is a side elevation of a pull propeller 20 corresponding with that shown in Fig. 1.

The propeller may be cast from suitable metal and comprises a conical or tapered body 5 whose smaller end is disposed forward and preferably rounded, as at 6, and said propeller body has diametrically opposite 25 straight diagonal channels 7 therein which lead from the front to the rear end of the body. Said channels are of substantially the same width and depth from end to end, so that they occupy considerably more of the circumference of the forward end portion of the body 5 than the circumference of the rear end thereof as seen in Fig. 2. The propeller body thus has curved surfaces of considerable 30 extent between the channels, and although two channels are shown it is possible to use more, but it is preferable to have them spaced apart sufficiently to provide the curved surfaces on the circumference of the propeller 35 between the channels, to provide for smooth action of the propeller in the water. The propeller also has considerable weight in order to serve as a fly or balance wheel.

The channels 7 have the walls 8 and 9, the propeller being intended to rotate clock-wise as seen in Figs. 2 and 3. The walls 8 "slope" inwardly with respect to the direction of rotation, while the walls 8 catch the water during the rotation of the propeller and give the propeller its propelling force.

The propeller has a screw or helix action in the water, and the tapered form of the propeller adds to its efficiency, the channels 7 being effective substantially throughout the length thereof owing to the fact that the channels diverge from the axis of rotation.

The propeller affords increased power, combined with smoother action and less churning of the water.

As shown in Fig. 1, the smaller end of the propeller is attached to the propeller shaft 10, with the propeller at the rear end of the shaft and serving as a push propeller, whereas as shown in Fig. 4 the propeller is secured on the forward end of the propeller shaft 10' to serve as a pull propeller. The propeller shown in Fig. 1 is used at the stern of a boat, while the propeller shown in Fig. 4 is used at the bow.

The channels 7 are of a width and depth in accordance with the power of the engine, and in being provided in the conical body will produce less vibration and shock on the engine than with bladed propellers.

The propeller may be used for land vehicles, as well as sleds, and may also be used for airships. When used in an airship the propeller is preferably constructed of light metal and is preferably hollow or of shell form.

Having thus described the invention, what is claimed as new is:

1. A propeller comprising a frusto-conical body, said body dished out to form straight diagonal channels of uniform width and depth extending from end to end of said body, relatively extensive portions between the channels for providing smooth action of the propeller in the water, and each of said channels having an abrupt inwardly extending wall and a wall extending substantially at a right angle to the first mentioned wall.

2. A propeller comprising a frusto-conical body having a pair of spaced channels, said channels diverging from end to end and of substantially uniform width, and relatively extensive portions between the channels for providing smooth action of the propeller in the water.

3. A propeller comprising a tapered body,

said body provided with straight diagonal channels of uniform width and depth and having relatively extensive portions between the channels for providing smooth propeller action in the water, and each of said channels having an abrupt inwardly extending wall and a wall extending at an angle to the first mentioned wall.

4. A propeller comprising a tapered body, 10 said body provided with straight diagonal channels of uniform width and depth and relatively extensive portions between the channels.

5. A propeller comprising a tapered body 15 provided with straight diagonal channels of uniform width.

6. The structure of claim 5, characterized by each of said channels having an abrupt inwardly extending wall.

20 In testimony whereof I hereunto affix my signature.

JUAN PEDRO RODRIGUEZ.
